UNITED STATES PATENT OFFICE.

ALESSANDRO FRANCHETTI, OF NEW YORK, N. Y., ASSIGNOR TO
DELAVERGNE MACHINE COMPANY, OF NEW YORK, N. Y.,
A CORPORATION OF NEW YORK.

ATOMIZING SPRAY-NOZZLE.

No. 657,566.

Specification of Letters Patent.

Patented June 18, 1907.

Application filed September 28, 1905. Serial No. 326,567.

To all whom it may concern:

Be it known that I, ALESSANDRO FRANCHETTI, a subject of the King of Italy, residing at present in the borough of Manhattan, city of New York, and State of New York, have invented certain new and useful improvements in Atomizing Spray-Nozzles for Oil-Engines and other Purposes, of which the following is a specification.

My improved atomizing spray nozzle is designed for use with oil engines in which the atomized fuel oil is injected into the working cylinder of the engine through a suitable valve by means of compressed air, and the purpose of my invention is to provide a simple and effective device for rapidly and completely atomizing the oil so as to supply the requisite spray of oil in the working cylinder of the engine.

The essential feature of my invention consists in providing two or more ducts or passage-ways leading from the oil and compressed air supplies and intersecting each other at a plurality of points, and leading to a common nozzle outlet for the escape of the resulting spray of oil. The action of the compressed air passing through the intersecting ducts or passages draws the oil through said passages, and at the points of intersection breaks up the oil into its atoms and thoroughly mixes it with the compressed air, this mixing and atomizing effect taking place over and over again at the successive intersections of the ducts or passage-ways until the action is complete when the mixture arrives at the nozzle outlet. By this means the atomizing of the oil can be accomplished with great speed. As a modification of this broad idea, I sometimes provide one or more enlarged spaces or chambers in the series of intersecting ducts or passage-ways, with the result of the change in speed of the passing compressed air and oil mixture from the small ducts or passage-ways to the enlarged spaces, and from the spaces back into the small ducts or passage-ways, and of storing a small quantity of fuel in these spaces so that, as to time, the opening of the spray valve may be independent of the working stroke of the fuel pump. By the continual crossing and re-crossing of the compressed air and oil in the process of atomizing and mixing, the oil is completely broken up into

its atoms with the use of a relatively small quantity of compressed air.

In order that my invention may be fully understood, I will first describe the same with reference to the accompanying drawings, and afterward point out the novelty more particularly in the annexed claims.

In said drawings Figure 1 is a detail view partly broken away showing the essential parts of a simple form of atomizing spray nozzle embodying my invention. Fig. 2 is a similar view of a slightly modified form of the same. Fig. 3 is a longitudinal sectional view of another form of atomizing spray nozzle embodying my invention.

Referring first to Fig. 1, it will be observed that the pipes or ducts 1 and 2 are arranged in zigzag form so as to intersect each other at intervals as shown at 3, 3 &c. The pipe 1 is designed to be connected with a suitable fuel oil supply usually controlled by a small oil pump in a manner well understood. The pipe 2 is designed to communicate with a supply of compressed air arranged in any suitable manner. 5 is a casing of a needle valve into which the intersecting oil and air pipes 1 and 2 lead through the common pipe 8. This needle valve casing 5 has a nozzle outlet 6 controlled by an ordinary needle valve 7 operating through the stuffing box 8 in a manner well understood. The nozzle 6 is designed to open into the working cylinder 9 of an oil engine, the supply of atomized oil being controlled by the needle valve 7 in the usual manner.

In Fig. 2 I have shown a slight modification in which the intersecting oil and air pipes 10 and 11 are of zigzag form as shown in Fig. 1, but have common pipe portions as shown at 12 and 13 leading into and out of the enlarged chambers or recesses 14 for the purpose of varying the velocity of the passing compressed air and oil during the process of atomizing and mixing. In this form of the atomizer the mixture of compressed air and oil is led into the needle valve casing 5 through the common pipe 15 in the same manner as above explained in connection with Fig. 1.

In Fig. 3 I have shown a further modification embodying a more practical form of my invention. In this form of the atomizing spray nozzle I have included the features of both of the forms shown in Figs. 1 and 2, in

that I include the intersecting ducts or passage-ways for the compressed air and oil, and the enlarged chambers or spaces for altering the velocity of the mixture during the atomizing operation. In Fig. 3, 20 is the cylindrical valve casing having a nozzle outlet 21 controlled by a needle valve 22, and the oil inlet 23 and compressed air inlet 24. The stem of the needle valve 22 passes rearwardly through a stuffing box 25 and is provided at its rear end with a head or collar 26 with which engages expansion spring 27, held in place by a suitable stop as shown at 28. An operating lever 29, journaled at 30 engages the head or collar 26 for operating the needle valve against the action of the spring 27, which latter normally holds the needle valve closed.

Mounted upon the stem of the needle valve 22, within the cylindrical casing 20, is a cylindrical head or piston 35 formed with two or more deep cylindrical grooves or recesses 36, which divide the piston into a plurality of piston sections which snugly fit the bore of the valve casing 20. The periphery of each of the piston sections is grooved or channeled with a series of intersecting ducts or passage-ways 37 and 38, which communicate at their ends with the spaces at the ends of the valve casing and with the spaces 36 between the piston sections.

The operation of the atomizing spray nozzle shown in Fig. 3 will be clear with but a few words of explanation. The oil and compressed air supply ports being properly connected with the supplies of oil and compressed air, and the outlet opening 21 of the nozzle being in proper position in the wall of the working cylinder of the engine, the needle valve is opened by the operation of the lever 29, through any suitable automatic mechanism, not shown, with the result that the compressed air rushing through the nozzle casing and intersecting ducts or passage-ways and enlarged spaces, will draw the oil through said intersecting passages and spaces at a great velocity, quickly breaking up the oil into its atoms, and thoroughly mixing it with the compressed air, discharging a perfect spray of oil into the cylinder of the engine.

I have shown several forms of devices for illustrating the purpose of my invention. I would have it understood that I do not limit

myself to any of these specific forms, but consider my invention to consist broadly of an atomizing spray nozzle having a plurality of ducts or passage-ways which intersect each other at a plurality of points and intervening chambers or recesses of larger capacity than the ducts or passage-ways, for rapidly and effectively atomizing oil through the use of compressed air. It will, of course, be understood that the intersecting ducts or passages may be arranged at any suitable or desired angle, so long as they accomplish the result pointed out, which is the atomizing of the oil and mixing it with the compressed air.

Having thus described my invention, what I claim as new and desire to secure by Letters Patent is:

1. An atomizing spray nozzle having a plurality of intersecting ducts or passage-ways, a common spray outlet communicating with the ducts or passage-ways, and intervening chambers or recesses of larger capacity than the ducts or passage-ways in which the fuel is stored when the common spray outlet is closed.

2. An atomizing spray nozzle comprising a nozzle casing having a spray outlet, a piston fitting within the nozzle casing and provided with a plurality of intersecting grooves or channels in its periphery, inlets to the casing for oil and compressed air, and a valve controlling the flow through the nozzle.

3. An atomizing nozzle comprising a casing having a spray outlet and compressed air and oil inlets, a needle valve controlling the spray outlet, and a piston mounted upon the needle valve and formed with a plurality of intersecting grooves or channels in its periphery for the passage and mixing of the air and oil.

4. An atomizing spray nozzle comprising a casing having a spray outlet and compressed air and oil inlets, a needle valve controlling the spray outlet, means for operating the needle valve, and a piston mounted upon the needle valve stem and formed in the periphery with a plurality of intersecting grooves or channels, and a plurality of circumferential grooves for the purpose set forth.

ALESSANDRO FRANCHETTI.
